& Hinckle Atty.

UNITED STATES PATENT OFFICE.

CHARLES E. SPENCER, OF CHICAGO, AND OWEN W. ROBERTS, OF OAK PARK, ILLINOIS,
ASSIGNORS, BY DIRECT AND MESNE ASSIGNMENTS, TO CASEMENT HARDWARE CO.,
OF CHICAGO, ILLINOIS, A CORPORATION OF ILLINOIS.

CASEMENT-WINDOW ADJUSTER.

Application filed March 13, 1925. Serial No. 15,396.

Our invention relates to casement window adjusters, and has particular reference to that type of adjuster having an arm or link pivotally supported on the stool or frame of the window and having its outer end 5 slidably supported in a guide carried on the window.

One of the objects of the invention is to provide an adjuster which is of very simple 10 and economical construction, which is operable with one hand, and which automatically and positively will fasten a casement window in open position and which readily may be adapted to all types of casement 15 windows.

Another object of the invention is to provide an adjuster so constructed that all of 20 its exposed surfaces may be painted for the sake of appearance and to resist rust.

Another object of the invention is to provide an improved construction of guide channel for mounting on the window.

Our invention has unique application to 25 metallic windows and metallic window frames, and for the purpose of showing a typical installation of the invention, we have shown the same mounted on a window and window frame of this construction, but it is to be understood that the invention is not 30 to be limited to use on metallic windows.

In the accompanying drawing illustrating 35 our invention:

Figure 1 is a fragmentary inside elevational view of a casement window to which 40 our adjuster has been attached;

Figure 2 is a horizontal sectional view 45 taken substantially on the plane of the line 2-2 of Figure 1, a portion of the guide being broken away to illustrate the fastening apertures and the pivotal mounting of the inner end of the link;

Figure 3 is a transverse sectional view 50 through the guide member and fastening slide, taken substantially on the plane of the line 3-3 of Fig. 1;

Figure 4 is a longitudinal sectional view 55 through the guide member, taken substantially on the plane of the line 4-4 of Figure 3;

Figure 5 is a detailed sectional view taken 60 substantially on the plane of the line 5-5 of Fig. 3, and

Figure 6 is a transverse sectional view

through the pivot bracket of the link, taken 55 on the plane of the line 6-6 of Figure 1.

The top, bottom and side rails of the 60 metallic window sash 9 consists of bars 11 having inner and outer parallel flanges 12 and 13 somewhat like Z-bars. The window frame 17 is constructed of a duplicate arrangement of bars 18 having parallel flanges 19 and 20 like the bars 11.

Secured to this window and window frame 65 is the present adjuster, which comprises the inner pivot bracket 22, which is secured to the window frame 17, the guide channel 23 which is secured to the window, and the link 24 which connects these two.

The pivot bracket 22 comprises a right 70 angle attaching portion 25 which is secured to the lower rail 18 of the window frame. For making this attachment, the inner flange 19 of this rail is notched out as indicated at 75 26 in Figure 1, and the angle portion 25 of the bracket is set into this notched out area. The horizontal leg of the angle portion is riveted or screwed to the web of the rail 18, as indicated at 27. This leaves a flush surface on both the inner and outer sides of the flange 19, thus permitting flush seating of 80 the flange 12 of the window along the inner flange of the frame rail, and presenting a neat appearing frame rail from the inner side of the window.

From the angle portion 25, the bracket 85 is bent back and then folded over to form a U-shaped portion 28, between the arms of which the link 24 is pivoted. A screw 29 passes through the U-shaped portion and through the link, threading into the bottom 90 of the U-shaped portion. It will be understood that this pivot bracket can be secured to the stool of the window frame, if desired.

The guide member 23 consists of a stamping 95 folded to provide a guide channel of box-like section (Figure 3) and comprises an outer vertical flange 31, a horizontal top flange 32, an inner vertical flange 33, and a bottom flange 34. The outer edge of the bottom flange 34 terminates short of the 100 outer vertical flange 31 to leave a slot 35 extending the length of the guide. Adjacent its ends, the guide member has depending portions 37 which are secured by rivets 38 to attaching angles 39. The inner flange 12 of the window is notched out at points ad-

5 jacent the ends of the guide member to receive the attaching angles, which are riveted to the webs of the window rails 11, as indicated at 41. This attachment leaves a flush inner face along the inner surface of the rail 11 for contacting with the flange 19 of the frame rail. At predetermined points along the bottom flange 34 of the guide there are provided fastening apertures 42 which, 10 as shown in Figure 5, are slightly elongated transversely of the guide. The sides of these apertures form fastening shoulders for cooperation with a fastening projection on the slider 44, which we shall now describe.

15 The releasing of the adjuster, the swinging of the window, and the refastening of the adjuster, is all performed through the direct manual operation of a liftable fastening slide 44 which is secured to the outer 20 end of the link 24 and slides in the guide 23. As shown in Figure 3, this manually liftable fastening slide consists of a stamping having a U-shaped portion 45 lying directly beneath the guide 23. The link 24 is secured in this dropped portion of the slider by a rivet 46. The inner end of the slide member passes up through the slot 35 and is provided with a backwardly bent hook flange 47 which rests upon the fastening 30 flange 34 of the guide. A fastening projection 48 is secured to this flange of the slider for reception in the fastening apertures 42 of the guide. This fastening projection has a reduced upper end which passes up 35 through the flange 47 and is riveted over on the upper side of a leaf spring 51. The upper ends of this leaf spring bear against the top wall 32 of the guide and press the projection 48 downwardly on the fastening 40 flange of the guide for snapping into the fastening projections 42.

45 As shown best in Figure 5, the outer wall of the slider is given a dull punching to project a rounded nipple or bearing projection 53 from its outer side for bearing against the adjacent wall of the guide. This rounded bearing contact maintains contact with the side wall of the guide in the slight pivotal turning of the slider member incidental 50 to the angular movement of the link.

55 The outer end of the slider is extended upwardly and looped over to provide an operating handle 55 in the form of a finger pull which the finger can be hooked under for raising the fastening slide and shifting it along the guide for opening or closing the window. Upon releasing this hook-like handle 55 the fastening projection 48 is allowed to snap into the end nearest adjacent 60 the fastening aperture 42 under the action of the leaf spring 51.

65 The pivot bracket 22 of the guide channel 23 and the link 24 are universal for right and left-hand windows. The only change which it is necessary to make in

70 adapting the adjuster to a left-hand window is the turning of the fastening slide 44 on the end of the link so that it will face in the opposite direction. The fastening apertures 42 may be given any desired arrangement 75 and spacing, it being generally desirable that there be a plurality of apertures adjacent the ends of the guide for relatively fine adjustment of the window in its substantially closed and wide open positions. The 80 similar spacing of these apertures adjacent the ends of the guide also adapts the guide to right and left-hand installations.

We claim:

1. The combination with a window frame 85 and a casement window sash hinged thereto, of an adjuster comprising a pivot bracket having an angle attaching portion, said angle attaching portion being set in a notched-out area of said window frame and secured thereto, a U-shaped upper end on said pivot bracket, a link pivotally supported between the arms of said U-shaped end, a box-like guide channel secured to said sash, said guide channel comprising a vertically extending flange secured to the inner side of the sash and a horizontal bottom flange, the edge of said horizontal bottom flange being spaced from said vertical flange to define a longitudinal slot therebetween, said bottom flange having a plurality of fastening apertures therein, a slider secured to the end of said link, said slider comprising an upwardly extending portion entering said longitudinal slot and a horizontal flange resting on the bottom flange of said channel, a fastening projection on the horizontal flange of said slider for reception in said apertures, a leaf spring secured to said slider and bearing against the top wall of said guide channel, and a finger pull comprising a part of said slider whereby said slider may be lifted vertically to disengage said fastening projection from said fastening apertures. 95

100 2. The combination with a window frame 110 and a casement window sash hinged thereto, of an adjuster comprising a pivot bracket supported by the window frame, an arm pivotally connected to said bracket, a guide channel secured to said window sash, said guide channel having a vertical flange and a horizontal flange spaced therefrom to provide a vertical slot in the bottom of said guide channel, a slider secured to the end of said arm, said slider comprising a vertically extending portion entering said slot and a horizontally extending portion resting on the horizontal flange of said guide channel, said horizontal flange having a plurality of fastening apertures therein, a fastening projection carried by the horizontally extending portion of said slider for engagement in said apertures, a leaf spring secured to said slider bearing against the top wall 115 of said guide channel and a handle extending 120 125 130

ing from said slider for lifting said slider vertically to release said fastening projection.

3. The combination with a window frame 5 and a casement window sash hinged thereto, of an adjuster comprising a stationary pivot bracket, an arm pivotally supported at one end on said bracket, a guide channel secured to said sash, said channel having a longitudinal slot in its bottom wall, a plurality of fastening shoulders in said guide channel, said slider comprising a portion entering said slot, a fastening pin on said last named portion adapted to co-operate with said 15 fastening shoulders, a spring secured to said slider and bearing against the top wall of said guide channel, and a handle extending from said slider by which the latter can be lifted to release said fastening pin from said 20 fastening shoulders.

4. The combination with a window frame and a casement window sash hinged thereto, of an adjuster comprising a stationary pivot bracket, an arm pivoted thereto, a box-like 25 guide channel secured to said sash, said guide channel having a slot formed in its under side, a horizontal flange along the inner side of said slot, said horizontal flange having a plurality of fastening apertures 30 therein, a slider connected to said arm and comprising a vertically extending portion entering said slot, a fastening projection carried by said slider within said guide channel adapted for engaging in said fastening apertures, and a handle extending from said 35 slider by which said slider can be lifted to release said fastening projection.

5. The combination with a window frame and a casement window sash hinged thereto, 40 of an adjuster comprising a stationary pivot bracket, an arm pivotally connected to said bracket, a box-like guide channel secured to said sash having a longitudinal slot in its under side, a slider having a hook-like portion entering said slot, a plurality of fastening apertures in one wall of said channel, a projection carried on the hook-like portion of said slider for engaging in said fastening apertures, and a handle extending from said 45 slider for moving said slider to release said fastening projection from said apertures.

6. The combination with a window frame and a casement window sash hinged thereto, 55 of an adjuster comprising a stationary pivot bracket, and an arm pivotally connected at one end to said bracket, a guide secured to said sash comprising top and bottom walls, one of said walls having a slot formed therein extending longitudinally of said guide, 60 one of said walls also having a plurality of fastening apertures therein, a slider secured to said arm, said slider comprising a vertically extending portion entering the slot in

said guide, a fastening projection carried by said vertically extending portion for engaging in said apertures, a spring carried 65 by said vertically extending portion of the slider and bearing against the opposite wall of said guide, and a handle extending from said slider for moving said slider vertically to release said fastening projection from 70 said apertures.

7. The combination with a window frame and a casement window sash hinged thereto, of an adjuster comprising a pivot 75 bracket, an arm pivotally connected at one end thereto, a box-like guide channel secured to said sash comprising front and rear side walls and top and bottom walls, said front and rear side walls being substantially closed, a longitudinal slot formed in said bottom wall, a slider secured to the other end of said arm, said slider comprising a portion entering said slot, a fastening projection on said slider adapted to engage in 80 fastening apertures in the bottom wall of said channel, and a handle portion extending from said slider for lifting said slider to release said projection from said apertures.

8. In a casement window adjuster, the 85 combination of a pivot bracket adapted for stationary mounting on a window frame, an arm pivotally connected to said bracket, a guide adapted for attachment to the casement sash, said guide comprising a lower 90 horizontally extending flange, fastening shoulders on said flange, a slider carried by said arm having fastening means adapted to engage said shoulders, said guide also comprising an upwardly extending flange, a 95 horizontally extending flange extending over said slider and a downwardly extending flange substantially enclosing said slider and the fastening shoulders on said lower flange and having a downwardly open slit 100 for said slider.

9. In a casement window adjuster, the 105 combination of a pivot bracket adapted for stationary mounting on a window frame, an operating arm pivotally connected to said bracket, a slider mounted on the end of said arm, and a guide for attachment to the casement sash, and adapted to receive said slider, said guide comprising a vertically extending attachment flange, a horizontally 110 extending flange, a second vertically extending flange in front of said slider, and a second horizontally extending flange, narrower than said first horizontally extending flange to retain said slider in said guide and 115 form a concealed slot along the side of said guide toward said operating arm.

In witness whereof, we hereunto subscribe our names this 9th day of March, 1925.

CHARLES E. SPENCER.
OWEN W. ROBERTS.
